(57) **CLAIM**

The ornamental design for a wearable therapeutic stimulation device having a retainer clip for a band, as shown and described.

DESCRIPTION

FIG. 1 is a front plan view of the wearable therapeutic stimulation device having a retainer clip for a band;
FIG. 2 is right side plan view of the new design;
FIG. 3 is lower edge plan view of the new design;
FIG. 4 is a back plan view of the new design;
FIG. 5 is a front perspective view of the right side of the new design;
FIG. 6 is a left side plan view of the new design;
FIG. 7 is an upper edge view of the new design;
FIG. 8 is a front plan view of the wearable therapeutic stimulation device having a retainer clip for a band when attached to a band;
FIG. 9 is right side plan view of the new design when attached to a band;
FIG. 10 is a left side plan view of the new design when attached to a band;
FIG. 11 is a back plan view of the new design when attached to a band;
FIG. 12 is a back perspective view of the left side of the new design when attached to a band; and,
FIG. 13 is a front perspective view of the right side of the new design when attached to a band.
The broken lines are for environmental purposes only and form no part of the claimed design.
